UNITED STATES PATENT OFFICE

WALTER B. SCHULTE, OF MADISON, WISCONSIN, ASSIGNOR TO BURGESS BATTERY COMPANY, OF MADISON, WISCONSIN, A CORPORATION OF WISCONSIN

DESIGN FOR A HAND LANTERN

Application filed July 17, 1931. Serial No. 40,582. Term of patent 14 years.

To all whom it may concern:

Be it known that I, WALTER B. SCHULTE, a citizen of the United States, residing at No. 123 W. Washington Ave., Madison, in the county of Dane and State of Wisconsin, have invented a new, original, and ornamental Design for a Hand Lantern, of which the following is a specification, reference being had to the accompanying drawings, forming part thereof.

I claim:

The ornamental design for a hand lantern, as shown.

WALTER B. SCHULTE.
